UNITED STATES PATENT OFFICE.

ARNOLD RUETSCHI, OF CLEVELAND, OHIO.

CLAM-SHELL BUCKET.

No. 882,844.

Specification of Letters Patent. Patented March 24, 1908.

Application filed June 3, 1907. Serial No. 376,934.

To all whom it may concern:

Be it known that I, ARNOLD RUETSCHI, citizen of the United States, resident of Cleveland, county of Cuyahoga, and State of Ohio, have invented a new and useful Improvement in Clam-Shell Buckets, of which the following is a specification, the principle of the invention being herein explained and the best mode in which I have contemplated applying that principle, so as to distinguish it from other inventions.

My invention relates to clam shell buckets its object being to provide a bucket that will be economical in construction and at the same time powerful and effective in its operation, with a minimum expenditure of energy.

A further object is to provide a bucket construction whereby an additional "reach" of scoop members is attained.

To the accomplishment of the above and related objects, said invention consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings: Figure 1 is a side elevation of one form of bucket embodying my several improvements, said bucket being shown in its closed position; Fig. 2 is an end elevation of the same, partly in elevation and partly in cross section, the bucket being likewise shown in closed position; Fig. 3 is a side elevation corresponding with Fig. 1, but showing the bucket in its open position; Fig. 4 is a side elevation of the bucket showing a slightly modified form of construction; and Fig. 5 is an end elevation, also of such modified form.

Referring first of all to the form of the bucket illustrated in Figs. 1, 2 and 3 inclusive, the frame of my bucket will be seen to comprise two side, or lateral, members A of substantially triangular form, Figs. 1 and 3, the upper corners of which are joined by a transverse bar A'. Corresponding lower corners of said two triangular side members are likewise joined by transversely disposed shafts A², that are designed to be fixedly held in such members. A vertical guide a, consisting simply of a rectangular bar, joins the ends of cross bar A' with the corresponding

horizontally disposed bases of triangular frames A, respectively. Slidably mounted between the two guides thus provided is a cross-head a', Figs. 2 and 5 that is designed to have a range of movement on such guides practically co-extensive with their length, or in other words, with the height of the frame. Rollers a² in such cross head reduce the friction that might otherwise tend to interfere with freedom of movement on the part of the cross-head.

Oscillatorily mounted on each of shafts A² are two oppositely disposed bell cranks B, to the lower arms b of which are pivotally hung the outer ends of two scoop members B' B'. The inner ends of such scoop members are connected by means of links b² b² with cross head a' vertically slidable as aforesaid in the bucket frame. Other links b³ join the upper arms b⁴ of bell cranks B with links b⁵, respectively. The weight of the oscillatorily hung scoops B' is designed to normally cause the latter to swing open, drawing thereby cross head a' downwardly so that the same occupies its lowermost position as shown in Fig. 3.

To draw such cross head upwardly between the guide ways a a suitable operating cable is required. The manner of connection of this cable will depend upon whether it is desired to operate the bucket as a double-line or a single-line bucket. In the first case, for use as a double-line bucket, cross bar A' will be suspended from the derrick boom, or an equivalent support, by means of a holding cable C secured at one end to a clevis c, or the like, attached to crossbar A', and secured at the other end to a winding drum. The operating cable C¹, connected with another drum of the hoisting engine, is conducted downwardly by a pulley c' in such cross bar A' around a sheave c² in the cross head then around a sheave c³ in the cross bar and again around a second sheave c² in the cross-head to a point c⁵ of attachment in the cross bar.

The mode of operation of the bucket where this is the method of line connection used should be quite obvious. The lower arms b, of bell cranks B, being extended substantially horizontally in the bucket's open position, the inner open ends of scoop members are given that much additional spread or reach. Upon cross-head a' being drawn upwardly to close the bucket, the scoop members are not merely oscillated about a fixed pivotal axis but bell cranks B are positively rocked at the same time so that

the inner ends of the bucket are swung upwardly and together. In other words such scoop members are moved bodily thus giving a real shoveling action with attendant increase in efficient application of power.

The arrangement of cable and sheaves where it is desired to operate the bucket with a single line is shown, in connection with the modified form of the bucket construction illustrated in Figs. 4 and 5. While the mode of line connection referred to may be incorporated in either form of bucket, it may be well first to describe the other modifications here introduced. These consist in the 15 substitution for fixed shafts A^2 of rock shafts A^3 upon which lever arms b^6 , corresponding with lower bell crank arms b , are fixedly mounted. In place of the two upper bell crank arms b^4 , a single upwardly extending 20 lever arm b^6 is necessary and this, by way of variation is shown as being connected by link b^3 directly to the cross-head a' instead of to links b^3 . The operation and action of the scoop members in this modified form of 25 bucket construction, it will be evident from the foregoing, departs in no wise from that of the previously described form. It will hence be understood that wherever I employ the term bell crank in this specification or in 30 the following claims, said term is meant equally to apply to this clearly equivalent structure.

Reverting finally to the single-line cable connection for the bucket it will be seen, 35 Figs. 4 and 5, that both ends of the line C^2 pass upwardly from the bucket. Of these ends the one is designed to be affixed to the end of the derrick boom, or other point of suspension of the bucket, the other end being 40 connected with a suitable winding drum as in the case of both the cables of the double-line arrangement. Such connections, being well known, have not been illustrated. The looped portion of the cable C^2 is passed two 45 or more times around sheaves c^2 and c^3 therefor provided in cross head a' and cross-bar A' . Such cable can accordingly be employed both to close the bucket and to raise the same when closed, dumping of the bucket 50 being effected by engaging clevis c with a hook at the lower end of a fixed depending cable. To retain the scoop-members of the bucket in their open positions pending the lowering of the latter again, it becomes necessary 55 to employ some form of latch. This consists preferably of a spring catch a^4 mounted upon the inner face of one of guides a and adapted to engage and hold the cross-head a' when in its lowermost position corresponding with the open state of the bucket. 60 This catch is designed to be just strong enough to hold the parts in such open position against their own weight, but not when the operating cable is drawn in to forcibly 65 close the same.

It should be added by way of conclusion that the adoption of a power sheave with actuating cable for drawing cross head a' upwardly, instead of the several arrangements of sheaves here shown, is also contemplated and is thought to be sufficiently obvious in its application not to require separate illustration.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a device of the character described, the combination of a frame; a cross-head vertically movable in said frame; scoop members pivotally attached at their outer ends to said frame; and links connecting the inner ends of said scoop members with said cross-head.

2. In a device of the character described, the combination of a frame; a cross head vertically movable in said frame; arms oscillatorily mounted in said frame on either side of said cross-head; scoop members pivotally attached at their outer ends to said arms; and links connecting the inner ends of said scoop members with said cross-head.

3. In a device of the character described, the combination of a frame; a cross head vertically movable in said frame; arms oscillatorily mounted in said frame on either side of said cross-head; scoop members pivotally attached at their outer ends to said arms; links connecting the inner ends of said scoop members with said cross-head; and means for positively rocking said arms.

4. In a device of the character described, the combination of a frame; a cross head vertically movable in said frame; arms oscillatorily mounted in said frame on either side of said cross-head; scoop members pivotally attached at their outer ends to said arms; links connecting the inner ends of said scoop members with said cross-head; and means connecting said arms with said cross-head whereby the former are positively rocked upon movement of the latter.

5. In a device of the character described, the combination of a frame; a cross-head vertically movable in said frame; bell-cranks oscillatorily mounted in said frame on either side of said cross-head; scoop members pivotally attached at their outer ends to the lower arms of said bell cranks, respectively; and links connecting the inner ends of said scoops and the upper arms of said bell-cranks with said cross-head.

6. In a device of the character described, the combination of a frame; a cross-head vertically movable in said frame; bell-cranks

oscillatorily mounted in said frame on either side of said cross-head; scoop members pivotally attached at their outer ends to the lower arms of said bell-cranks respectively; 5 links connecting the inner ends of said scoop members with said cross-head; and other links connecting the upper arms of said bell cranks with said first named links.

7. In a device of the character described, 10 the combination of a frame provided with vertically disposed guides; a cross-head movable between said guides; oppositely disposed bell-cranks oscillatorily mounted in said frame on either side of said cross-head; 15 two scoop members pivotally attached at their outer ends to the lower arms of said bell-cranks, respectively; links connecting the inner end of said scoop members with said cross-head; and other links connecting the upper arms of said bell-cranks with the lower portions of said first named links. 20

8. In a device of the character described, the combination of a frame comprising two lateral members of substantially triangular

outline, a bar joining the upper corners of said members, and two shafts respectively joining the lower corners of the same; vertical guides in said lateral frame members; a cross-head slidably mounted between said guides; bell-cranks oscillatorily mounted upon said shafts 30 respectively; two scoop members pivotally attached at their outer ends to the lower arms of said bell-cranks, respectively; links connecting the inner end of said scoop members with said cross-head; other links connecting the upper arms of said bell-cranks with the lower portions of said first named links; sheaves mounted in the bar of said frame and in said cross-head, respectively; and an actuating cable passing around said 35 sheaves for drawing the latter towards the former.

Signed by me this 31st day of May, 1907.

ARNOLD RUETSCHI.
